UNITED STATES PATENT OFFICE.

CHARLES G. SHEPARD AND PETER ADAMS, OF BUFFALO, NEW YORK; SAID ADAMS ASSIGNOR TO WALTER J. SHEPARD, OF SAME PLACE.

DESIGN FOR A TOY SAVINGS-BANK.

SPECIFICATION forming part of Design No. 17,103, dated February 8, 1887.

Application filed January 3, 1887. Serial No. 223,336. Term of patent 7 years.

To all whom it may concern:

Be it known that we, CHARLES G. SHEPARD and PETER ADAMS, of the city of Buffalo, in the county of Erie and State of New York, have invented and produced a new and original Design for Toy Savings-Banks, of which the following is a specification.

This design relates to the general configuration of an ornamental toy savings-bank, which is clearly represented in the accompanying drawing, making part of this specification.

A represents the elongated base of the savings-bank, provided at one end with a raised portion, B, representing a brick wall or portion of an unfinished building.

C represents the figure of a man standing behind the wall and holding in his right hand a trowel and in his left hand a brick.

D represents the figure of a man standing on the base A, facing the wall B, and carrying on his shoulder a hod, E.

F represents a pail, and G a mortar-receptacle resting on the base A.

We claim as our invention—

The design for a toy savings-bank, consisting of a wall, B, the figure of a man standing behind said wall, and the figure of a man standing in front of said wall, substantially as shown and described.

Witness our hands this 22d day of December, 1886.

CHARLES G. SHEPARD.
PETER ADAMS.
